UNITED STATES PATENT OFFICE.

WILLIAM E. BELKE, OF CHICAGO, ILLINOIS.

PROCESS AND APPARATUS FOR ELECTROPLATING.

1,426,141.

Specification of Letters Patent. Patented Aug. 15, 1922.

Application filed March 15, 1922. Serial No. 543,889.

To all whom it may concern:

Be it known that I, WILLIAM E. BELKE, a citizen of the United States, and a resident of Chicago, Cook County, Illinois, have invented a certain new and useful Improvement in Processes and Apparatus for Electroplating, of which the following is a specification.

This invention relates to electroplating in general, and more particularly to methods or processes of this kind in which a tank or other receptacle is provided for the electroplating solution in which the work is done. Obviously, a tank of this kind must be kept open when in use, so that the work may be readily handled. Consequently, of course, dirt and dust from various sources are liable to enter the tank. Even the object to be plated very often carries with it more or less foreign matter, and the chemical action which takes place during the plating operation causes a precipitation of various substances. Foreign matter of this kind is detrimental to the work, and results in blemishes or discolorations or pinholes or other defects on the surface of the deposit. Impurities in the electroplating solution are, therefore, quite liable to interfere very seriously with the efficiency of the electroplating apparatus, and to result in an inferior or poor grade of plating work.

Generally stated, therefore, the object of the invention is to provide an improved construction and an improved method or process whereby the electroplating solution is drawn from the tank or other receptacle, by suction produced by a jet of compressed air, or by other suitable means, and is then filtered and returned to the tank or other receptacle, by filtration means of any suitable character, thus continuously eliminating the foreign matter or impurities from the solution, and ensuring better results in the work of electroplating various objects, as will hereinafter more fully appear.

It is also an object to provide certain details and features of improvement tending to increase the general efficiency and desirability of an electroplating process or method of this particular character.

To this and other useful ends the invention consists in matters hereinafter set forth and claimed and shown in the accompanying drawings in which—

Figure 1 is a perspective of an electroplat-

ing apparatus having filtration means embodying the principles of the invention.

Figure 2 is an enlarged detail sectional view of a portion of said filtration means.

As thus illustrated, the invention comprises a tank 1, or a receptacle of any suitable or desired character, in which the electroplating solution is held. Said solution, of course, may be of any suitable or desired character, depending upon the character of the work to be done. For the purpose of continuously filtering the solution, an intake pipe 2 having openings 3 in the sides thereof is arranged to extend along the bottom of the tank, and is provided with an upwardly extending portion 4 which is coupled at its upper end to the base 5 of the filtration means, said base being secured to the tank or any suitable support in any suitable or desired manner. The solution is sucked in through the openings 3, by the air jet discharged upwardly in the pipe 4 from the small compressed air pipe 6, and is discharged from the top of the pipe 4 into the hollow head 7 of said filtration means, and from said head into the filter bag 8, which latter may be of any suitable or desired material, depending upon the character of the solution. There are well known materials which are not attacked by the various solutions employed in electroplating, and any of these materials may be used for this purpose, the meshes of the head being fine enough to prevent dirt and sediment and other foreign matter from passing through, but being open enough to permit the solution itself to flow through easily and back into the tank. This filter bag is removably attached to the bag at 9 by a screw connection of any suitable character, or in any suitable or desired manner. The compressed air is supplied to the pipe 6 from a main pressure pipe 10 through a valve 11 by which the force of the upwardly directed jet from pipe 4 may be controlled at will, and whereby the jet may be shut off entirely when such is necessary or desirable. It is desirable to eliminate the air from the solution, before the latter passes into the filter bag 8, and this may be done in various ways. For example, a hollow trap 12 may be provided to extend upwardly on the base 5, into which the air from the solution will pass and be held,

while the solution thus segregated from the

air will then pass through the head 7 and into the filter bag. A small relief valve 13, or outlet of any suitable character, may be provided on one side of the air trap 12 to permit the escape of the air in a manner that will not create too much back pressure, but only enough to keep the solution from rising in the trap 12, thereby to compel the solution to pass in the other direction and enter the filter bag. The dirt or impurities or foreign matter will naturally settle, more or less, to the bottom of the tank, and it will be sucked into the openings 3 with the liquid solution; and will be caught and held by the bag 8, which latter can be cleaned from time to time in order to dispose of the accumulation of dirt and foreign substance therein. Thus the solution is filtered after it is forcibly drawn or sucked from the tank and before it is again discharged into the top of the tank in purified form, having been filtered and thereby reduced to a better condition for use in the electroplating work. Gradually, therefore, dirt and impurities and precipitates and other foreign substances are eliminated from the solution, so that the electroplating work may proceed with higher efficiency, and with better results, and with less liability of blemishes or discolorations or pinholes or other defects on the surface of the work. A further beneficial action is obtained by agitation of the solution, and this is preferably done by bubbling the solution, or by aeration, so to speak, so that the solution is maintained in an agitated condition which not only produces certain beneficial effects heretofore obtained by agitation, but it also renders the filtration apparatus more effective. For example, a zigzag pipe 14 having outlets 15 therein may be placed on the bottom of the tank and connected with the riser 16, the latter being in turn connected by a valve 17 with the main compressed air pipe 10 previously mentioned. It will be seen that the previously mentioned pipe 2 is arranged to rest on the pipe 14, and with this arrangement air is forced down through the pipe 16 and into the pipe 14 and out through the openings 15 into the solution, thereby causing a bubbling action, resulting in the desired agitation of the solution, and aeration of the liquid. Thus air agitation is combined with filtration of the solution, in the manner shown and described, so that the work not only has the advantage of the agitation to ensure better results, but also the beneficial action resulting from the filtration of the solution. The filtering action is facilitated by the agitation, as the air injected into the solution stirs up the sediment or foreign matter, and in this way the solution with the foreign matter in suspension passes through the openings 3 previously mentioned and into the pipe 2 and then up and into the filter in the manner explained. It is true, therefore, that not only is the solution filtered in this manner, by lifting or drawing the solution upward by means of an air jet, but also that the solution is agitated by air during the circulation and filtering of the solution. Again, as a matter of still further and special improvement, in conjunction with the filtration of the solution, a vertically disposed reservoir 18 is provided for the head 7, in position to discharge downwardly toward the filter bag 8, in the manner shown in Figure 2 of the drawings. For this purpose a fine wire mesh strainer 19 is provided at the top of the filter bag to receive the discharge from the reservoir or magazine 18, it being understood that this tubular magazine 18 is provided at its upper end with a removable cover 19 to permit the filling of the tube with any suitable or desired substance, depending upon the chemical action to be obtained. The salts 20, or other substance, feed gradually downward in the magazine 18 and rest upon the strainer 19 in position to intercept the solution as the latter flows from the head 7 into the filter bag. In other words, the solution must pass through the salts or other substance 20 before it can enter the filter bag, and in this way the solution can be subjected to any desired or beneficial action before it is returned to the tank, in addition to being filtered and thereby relieved of the impurities or foreign matter. With this system, therefore, the solution is continuously subjected to four things, successively as follows: First, the air agitation thereof in the tank; second, the raising or drawing of the agitated solution upward by the jet of air; third, the interception of the solution, after the air is freed therefrom, by the salts or other substance 20 in the magazine 18 as stated; and fourth, the filtering of the solution by the filter bag 8 before it is discharged by gravity on to the upper surface of the body of the solution in the tank. All this, of course, tends to ensure better results in the work of metal plating any suitable or desired object which may be immersed in the solution, and ensures against blemishes or defects of other kinds on the surface of the metallic deposit of such object. The relief valve 13 has a pipe 21 which extends upward in the air trap 12 to a point near the top of the latter, so that the solution can rise quite a distance therein before it overflows into the pipe and out through said valve. If the valve 13 is closed enough, the air pressure in the top of the trap will prevent the solution from rising very much therein, as

might be the situation for some purposes; but for other kinds of work the relief valve 13 will be wide open to prevent any back pressure of the air, and the solution will 5 overflow through the pipe 21 if it does not flow fast enough through the filter bag, as might be the case if the latter becomes clogged to some extent. It is understood, of course, that the apparatus shown and 10 described is merely illustrative of the invention, for the invention in its broader aspects is not limited to any particular form of apparatus.

What I claim as my invention is—

15 1. In a process of electroplating, the circulation of the electroplating solution from the body thereof to a point above the body of the solution and the filtering of the solution thus drawn off before it is discharged on to the top of the body of said solution.

20 2. A process as specified in claim 1, including the use of an air jet to raise the solution and force it upward to said point where it is filtered and returned to the body of the solution.

25 3. A process as specified in claim 1, including the use of air pressure to circulate the solution upward to said point of filtration thereof, and the elimination of the air from the solution before said point of filtration is reached.

30 4. A process as specified in claim 1, comprising the use of a jet of air to suck the solution into the path of circulation and to force the same upward to the point of filtration thereof, and releasing the air from the circulating portion of the solution before it reaches said point of filtration, so that the 35 released air escapes in one direction while the solution is filtered and allowed to return by gravity in purified condition to the said main body of the solution.

40 5. The process as specified in claim 1, comprising in addition the agitation of the main body of the solution to facilitate the gradual elimination of the impurities or foreign matter by said circulation and filtration of the solution.

45 6. A process as specified in claim 1, including also the agitation and the bubbling of the main body of the solution by jets of air at the bottom thereof, whereby the solution is aerated and agitated before being raised to point of filtration thereof.

50 7. A process as specified in claim 1, including the passage of the circulating solution through any desired substance before reaching the point of filtration thereof,

whereby to produce the desired chemical effect on the solution before being filtered.

55 8. A process as specified in claim 1, including the automatic feeding of soluble salts into the path of the circulating solution, before the solution reaches the point of filtration thereof, thereby to produce the desired effect.

9. In electroplating apparatus, the combination of a receptacle to hold the main body of the electroplating solution, means to circulate the solution from the body thereof and then upward to a point over the body of the solution, means to filter the solution before it is returned by gravity to the top of the solution in the said receptacle, and means for forming a jet of air in the path of circulation of the solution to raise the latter to said point of filtration thereof.

10. Apparatus as specified in claim 9, comprising means to release the air from the solution before the latter reaches said point of filtration thereof.

11. Apparatus as specified in claim 9, comprising a reservoir for automatically feeding any desired substance into the path of the solution before the latter reaches the point of filtration thereof.

12. Apparatus as specified in claim 9, in combination with means for using air to agitate the main body of the solution.

13. In a process of electroplating, the circulation of the electroplating solution from the body thereof to a point above the body of the solution and the filtering of the solution thus drawn off before it is discharged on to the top of the body of said solution, comprising the use of a jet of air to suck the solution into the path of circulation and to force the same upward to the point of filtration thereof, and releasing the air from the circulating portion of the solution before it reaches said point of filtration, so that the released air escapes in one direction while the solution is filtered and allowed to return by gravity in purified condition to the said main body of the solution, including also the agitation and the bubbling of the main body of the solution by jets of air at the bottom thereof, whereby the solution is aerated and agitated before being raised to the point of filtration thereof.

14. A process as specified in claim 13, including the passage of the circulating solution through any desired substance before reaching the point of filtration thereof, whereby to produce the desired chemical effect on the solution before being filtered.

WILLIAM E. BELKE.
